Associates, a corporation of California

Application January 14, 1954, Serial No. 404,040

5 Claims. (Cl. 315—3.5)

This invention relates in general to electron beam discharge apparatus and methods and, more particularly, to novel devices of the slow wave type such as, for example, traveling wave tubes and backward wave oscillators which utilize novel electrostatic focusing methods and apparatus.

One object of the present invention is to provide an electron beam device such as a traveling wave tube or backward wave oscillator of interdigital construction wherein one set of the interdigital members or fins is electrically insulated from the other associated set of fins.

Another object of the present invention is to provide a novel slow wave structure of the type referred to in the immediately preceding object wherein the two sets of interdigital fins are maintained at different relative values of potential.

Another object of the present invention is to provide a novel electron beam device having a slow wave structure which electrostatically focuses the beam, whereby the use of permanent or electromagnets for focusing is either unnecessary or the amount of magnetic field required for focusing is substantially reduced.

Still another object of the present invention is to provide a novel device of the above character having a slow wave structure of the interdigital type wherein one set of interdigital fins is structurally different from the associated second set of fins to compensate for the alternate changes in beam velocity due to the beam focusing electric field components parallel to the electron beam which are directed in alternately opposite directions between successive pairs of fins.

These and other objects and advantages of the present invention will be more apparent after a perusal of the following specification taken in connection with the accompanying drawings, wherein

Fig. 1 is a longitudinal sectional view of an electron beam device illustrated as a traveling wave tube amplifier of the interdigital fin type construction wherein the electron beam passing through the tube is electrostatically focused,

Fig. 2 is a cross-section view of the traveling wave tube amplifier taken along section line 2—2 in Fig. 1,

Fig. 3 is a diagrammatic view showing the electric field lines between successive pairs of the interdigital fins of the traveling wave amplifier device shown in Fig. 1, and

Fig. 4 is a diagrammatic section view of an embodiment of the present invention wherein alternate fins in the interdigital structure are of a different configuration than the fins in the remaining set of interdigital fins to compensate for velocity changes in the beam due to the electric field lines.

Referring now to Figs. 1 and 2, the traveling wave tube amplifier which embodies the novel interdigital structure of this invention comprises a main body portion 1 of substantially an elongated U-shape configuration and a top portion 2 also of U-shape cross section which is adapted to fit onto the main body portion 1 and form the hollow elongated tube body, these bodies being of a good con-

2

ducting metal such as copper or plated with a good conducting metal. Mounted on the right-hand end of the body is a collector assembly which comprises a metallic electron collector 3, an end adapter 4 and an insulating seal 5 as of glass. Secured on the left-hand end of the tube body is a cathode assembly which comprises the gun anode 6, the cathode gun assembly 7 including the cathode button 7', and the insulating mounting seal 8 as of glass.

Secured on the main body portion 1 and extending upwardly within the tube body are a plurality of equally spaced metallic fins or loading members 9. Mounted within the tube body is a substantially U-shaped elongated member or plate 11, the plate being mounted on the main body 1 and insulated therefrom by insulating spacers 12. The plate 11 is spaced from the wall 2 of the body and electrically insulated therefrom by suitable spacers 13 as of ceramic. Mounted on this plate 11 and extending downwardly within the tube are a plurality of equally spaced fins or loading members 14, these fins 14 being so arranged as to form a uniform interdigital structure with the fins 9 along the length of the tube. A small aperture 15 is located in each of the fins 9 and 14, these apertures being in axial alignment with the cathode button 7' and the collector 3 so that a clear path is provided for the electron beam from the cathode through the interdigital structure to the collector. A substantially L-shaped member 16 is provided on either side of the tube for utilization as a choke.

An input waveguide 17 having an associated window seal 18 is coupled through an aperture in the body portion 1 to the space between the first set of fins 9 and 14 on the left-hand side in Fig. 1. An output waveguide 19 with its associated window seal 21 is coupled through a second aperture in the main body portion 1 to the space between the furthermost set of fins 9 and 14 on the right-hand side of the tube. The cathode is connected to a source of potential 22 which places the cathode at a negative potential with respect to the main body of the tube and the collector 3. The insulated plate 11 and associated fins 14 are connected to a source of potential 23 which maintains this plate and fin assembly at a positive potential with respect to the main body portion 1 and associated fins 9.

In operation, a stream of electrons, shown in dot-dash lines in Fig. 1, is emitted from the cathode button 7' and is accelerated by the positive voltage on the gun anode, the stream of electrons being focused into a beam while passing through the aperture in the gun anode 6. The beam of electrons proceeds along the path defined by the apertures 15 in the interdigital structure. The expended beam of electrons is then collected by the positively charged collector electrode 3. The wave energy to be amplified is transmitted into this traveling wave amplifier through the input waveguide 17, the wave energy traveling in a sinuous path along the interdigital structure defined by the fins 9 and 14 such that the wave travels along the tube at the same velocity as the electron beam in a well-known manner and extracts energy from the beam. The amplified wave energy is extracted from this traveling wave tube through the output waveguide 19.

This novel construction of a slow wave tube is utilized in cooperation with selected electric potentials to electrostatically focus the electron beam so that the beam retains its small cross-section as it proceeds along the length of the tube, thus eliminating the necessity for a magnetic field focusing means such as a permanent magnet or electromagnetic coils. As stated above, the plate 11 and fins 14 are at a potential positive with respect to the main body portion 1 and fins 9 and thus an electric field is produced between the fins 9 and the fins 14. The electric field pattern set up between the interdigital fins which

would produce the optimum electron beam focusing is shown in part in Fig. 3 by the arrowed lines. The electric field lines are shown in the direction of electron deflection. In the absence of the apertures, the electric field lines between the fins would be parallel with the axis of the beam and essentially constant across the position of the apertures. With the apertures present, the electric field pattern in the beam path has both longitudinal and circularly symmetric radial components of electric field. The longitudinal component causes the velocity of the electrons in the axial direction to vary. When the electron velocity is smaller than the average, the radial component of electric field produces an inward force, and when the velocity is larger, the radial electric field produces an outward force. Because of the velocity variation, however, the electrons spend more time in the region of inward force and hence acquire a net inward momentum from the focusing field. This can be used to balance the outward momentum due to electron repulsion forces which continually act within the beam, and would cause the beam to diverge if no focusing forces were present.

One other effect which may, in some instances of utilization of the novel electrostatic focusing scheme, give rise to undesired operation is that the electric field between one interdigital fin 9 and its immediately preceding associated fin 14 is in one particular direction while the electric field between the same interdigital fin 9 and the immediately succeeding interdigital fin 14 is in the opposite direction. Thus the first mentioned field is in the direction which opposes the electron flow while the other field is in the direction which aids the electron flow and therefore the velocity of the electrons as they enter any one interdigital fin 9 is less than the velocity when they enter the succeeding interdigital fin 14. Thus, the transit angle through the fins 9 is greater than the transit angle through the fins 14, the cumulative effect of which may be sufficient to destroy the required phase relationship with the radio-frequency wave. To remedy this effect the novel structure shown in Fig. 4 may be utilized where the thickness of the fins 14 is greater than the thickness of the fins 9 so that the transit angles through the fins 9 and 14 may be made equal.

Since many changes could be made in the above construction of this invention, for example, various shapes and sizes of interdigital members may be employed in various types of electron tube devices, and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A slow-wave electron beam device of the type wherein an electromagnetic wave is made to travel through the device coupled to and substantially at the velocity of an electron beam therein such that an energy exchange occurs between the beam and the wave comprising means for producing a beam of electrons directed through said device, a slow-wave structure associated with the beam path comprising an interdigital structure having a first plurality of loading members electrically coupled together and a second plurality of loading members electrically coupled together, said loading members having apertures therein aligned with the beam path, said loading members being interdigitally spaced along the beam path whereby a sinuous wave-energy path is formed defined by the loading members for the transmission of said electromagnetic wave in a sinuous path directed along and coupled to said beam, means electrically insulating said first plurality of loading members from said second plurality, and means for applying different direct current electrical potentials to said two pluralities of loading members such that electrostatic focusing fields extend between adjacent loading members at the beam path apertures for focusing the beam.

2. A slow-wave electron beam device of the type wherein an electromagnetic wave is made to travel through the device coupled to and substantially at the velocity of an electron beam therein such that an energy exchange occurs between the beam and the wave comprising means for producing a beam of electrons, a base member having a plurality of equally spaced loading members mounted thereon and extending inwardly into the device, a top plate positioned above said base member having a plurality of equally spaced loading members mounted thereon and extending toward the base member, said latter loading members being in interdigital relationship with said former loading members such that a sinuous wave-energy path is formed through the device defined by the loading members, said loading members each having an aperture therein, the apertures being aligned within the device so as to be aligned with the electron beam path therethrough such that the electron beam is coupled to the electromagnetic wave passing along the sinuous path for energy exchange, means for mounting said top plate on said base member including insulation electrically insulating the top plate from the base member, and means for applying different direct current electrical potentials to said base and top plate whereby an electrostatic focusing field may extend between adjacent loading members at the beam path apertures.

3. A slow-wave electron-beam device of the type wherein an electromagnetic wave is made to travel through the device coupled to and substantially at the velocity of an electron beam therein such that an energy exchange occurs between the beam and the wave comprising means for producing a beam of electrons directed through said device, a slow-wave structure associated with the beam path comprising a first plurality of loading members electrically coupled together and a second plurality of loading members electrically coupled together, the members of the two pluralities being alternately spaced along the beam path in interdigital relationship such that a sinuous wave-energy path is formed through the device defined by the loading members, said loading members having apertures therein aligned with the beam path, and means electrically insulating said first plurality of loading members from said second plurality, a source of electrical potentials, means for coupling the first and second pluralities of members to said source whereby said first and second pluralities are at different relative potentials such that focusing electrostatic fields extend between adjacent loading members at the beam path apertures, the dimension of the loading members in the direction of the beam path of one plurality of loading members being greater than the dimension in the direction of the beam path of the loading members of the other plurality.

4. A slow-wave electron beam device of the type wherein an electromagnetic wave is made to travel through the device coupled to and substantially at the velocity of an electron beam therein such that an energy exchange occurs between the beam and the wave comprising means for producing a beam of electrons directed through said device, a slow-wave structure associated with the beam path comprising a first plurality of loading members electrically coupled together and a second plurality of loading members electrically coupled together, the members of the two pluralities being alternately spaced along the beam path in interdigital relationship such that a sinuous wave-energy path is formed through the device defined by the loading members, said loading members having apertures therein aligned with the beam path, the dimension of each of the first plurality of loading members in the direction of the beam path being different than the like dimension of each of the second plurality of loading members, means electrically insulating said first plurality of loading members from said second plurality, and means for applying different direct current electrical potentials to said two pluralities of loading members such that electrostatic

focusing fields extend between adjacent loading members at the beam path apertures.

5. A slow-wave electron beam device of the type wherein an electromagnetic wave is made to travel through the device coupled to and substantially at the velocity of an electron beam therein such that an energy exchange occurs between the beam and the wave comprising means for producing a beam of electrons, a base member having a plurality of equally spaced loading members mounted thereon and extending inwardly into the device, a top plate positioned above said base member having a plurality of equally spaced loading members mounted thereon and extending toward the base member, said latter loading members being in interdigital relationship with said former loading members such that a sinuous wave-energy path 15 is formed through the device defined by the loading members, said loading members each having an aperture therein, the apertures being aligned within the device so as to be aligned with the electron beam path therethrough, the dimension in the direction of the beam path of each of 20 said latter loading members being different from the like dimension of each of said former loading members, and

means for mounting said top plate on said base member including insulation electrically insulating the top plate from the base member whereby different direct current electrical potentials may be applied to said base and top plate such that electrostatic focusing fields extend between adjacent loading members at the beam path apertures.
